UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A METAL BORDER.

SPECIFICATION forming part of Design No. 21,848, dated September 6, 1892.

Application filed August 4, 1892. Serial No. 442,186. Term of patent 3½ years.

To all whom it may concern:

Be it known that I, CHARLES OSBORNE, of New York city, in the county and State of New York, have invented a new and original 5 Design for a Metal Border, of which the following is a full, clear, and exact description.

The design is for an ornamental metal border for use on metal-work, and especially dishes of various kinds.

10 Reference is to be had to the accompanying drawing, forming a part of this specification, in which the figure is a perspective view of the border produced on a flat strip of metal.

15 The leading feature of my design is the serpentine figure produced in relief and having

an ornamented surface. The serpentine figure is produced in relief on the surface to be ornamented, and the surface of the serpentine figure has a roughened bark-like effect produced by the overlapping irregular leaf-like figures. At alternate bends or convolutions of the serpentine figure are produced flower-like figures, these simulating roses.

I claim—

. The design for a metal border herein shown 25 and described.

CHARLES OSBORNE.
